UNITED STATES PATENT OFFICE.

WILLIAM KERR, OF PHILADELPHIA, PENNSYLVANIA, ASSIGNOR TO VAN
DEVENTER & HORNE, OF NEW YORK, N. Y.

DESIGN FOR A CARPET.

SPECIFICATION forming part of Design No. 13,114, dated August 1, 1882.

Application filed June 26, 1882. Term of patent 3½ years.

To all whom it may concern:

Be it known that I, WILLIAM KERR, of Philadelphia, in the State of Pennsylvania, have invented a certain Improved Design for Carpets, of which the following is a specification.

This design is intended for the ornamentation of carpets, and relates to the pattern hereinafter described, and represented in the accompanying photograph. This pattern is not limited to any particular colors, and the same is to be employed in carpets, whether woven as a three-ply or ingrain carpet, or as a piled fabric, such as brussels or tapestry.

The groundwork of the design is mottled in its appearance, and there are vines running diagonally across the carpet, having tortuous stems and branches, as at *a*, with leaflet-patterns, as at *b*, compound leaflets, as at *c* and

d, blossoms at *e e'*, and buds at *f f'*, all as represented. The patterns are repeated in the arrangement shown, so that the pattern on one piece of carpet matches out and forms a continuation of the branches and vines in the next.

I claim as my invention—

The design for carpets, consisting of the tortuous stems and branches extending in a diagonal direction, with the leaflets *c d*, blossoms *e e'*, and buds *f f'*, arranged and repeated substantially the manner set forth.

Signed by me this 15th day of June, A. D. 1882.

WILLIAM KERR.
